UNITED STATES PATENT OFFICE.

WILLIAM S. ORTH, OF DUNKIRK, OHIO.

CALENDAR.

1,236,974.

Specification of Letters Patent. Patented Aug. 14, 1917.

Application filed March 15, 1916. Serial No. 84,309.

To all whom it may concern:

Be it known that I, WILLIAM S. ORTH, a citizen of the United States, and a resident of Dunkirk, in the county of Hardin and 5 State of Ohio, have invented certain new and useful Improvements in Calendars, of which the following is a specification.

My invention relates to calendars, and the main object thereof is to provide such a device of the perpetual type wherein it is not necessary ever to reverse any of the cards at the end of a day, week, month, or year, in order to begin a new period, said cards always being turned in the same direction.

15 A further object is to provide card suspension devices of special type, particularly for the central series, whereby the daily, weekly, or monthly turnings above referred to are rendered very easy.

20 My invention is fully described in the following specification, of which the accompanying drawings form a part, in which like characters refer to like parts in each of the views, and in which:—

25 Figure 1 is a perspective view of my calendar in desk form, showing an intermediate step in turning the foremost card of the bottom series to the rear;

Fig. 2 is a front face view thereof, ready 30 for use;

Fig. 3 is a fragmentary detail section taken on the line 3—3 of Fig. 2; and

Fig. 4 is a detached view of a detail.

35 My invention comprises a frame formed of wire, carrying a plurality of series of cards suitably designated, each series being carried by wire rings of a size permitting the free card swinging movement.

The desk form shown in Figs. 1 to 3, inclusive, comprises a frame 7 formed of side members 8 held together by two horizontal rods 9 and 10, each of which rods is rigidly held and provided with depending looped portions 11 adjacent their ends, each side member 8 being formed of a length of wire bent centrally into a loop and the ends downwardly directed and outwardly flared to provide foot members 8^a, the ends of the rods 9 and 10 being secured between the parallel portions 8^b of the side members 8.

Depending from the loops 11 of the rod 9 are rings 12, preferably of the split variety, passed through registering holes 13 of a series of cards 14, this series bearing the

name or abbreviation of the days of the week and, being, accordingly, seven in number, the day designations being the same at each side of the calendar, though not on each side of each card.

Depending from the loops 11 of the rod 60 10 are split rings 15 passed through holes 16 in a series of cards 17 bearing the numerals from 1 to 31 representing the dates of a month, the same numeral appearing upon opposite sides of the calendar, and, 65 because of this manner of suspending the series of cards, the turning of one or more upwardly and backwardly is simple and easy.

Looped over the ends of the rod 9 is a 70 yoke 18 of a height permitting free swinging thereof beneath the series 14 of cards but at a material height above the rod 10, the horizontal portion of this yoke having loops 19 formed therein similar to the 75 loops 11.

Depending from these loops 19 are split rings 20 passed through holes 21 in a series of cards 22 of a height permitting free swinging thereof above the rod 10, this series of cards bearing the monthly designations, and revealing the same designations upon opposite calendar sides, there being twelve of these cards, as will be obvious.

The yoke 18 forms an important part of 85 my calendar inasmuch as when it is desired to turn one of the cards 17 to the back said yoke and the cards 22 suspended therefrom are swung rearwardly sufficiently far to permit the card 17 being moved to clear said 90 yoke and cards 22.

Similarly, the series of cards 14 may be swung rearwardly to permit the clearance of a card 22 which is to be swung to the rear, but the turning back of one of the cards 14 95 is possible without disturbing the positions of the other series of cards. As soon as the cards so disturbed are released they return to normal positions by gravity, as will be seen, and, in the daily, and monthly, turnings of the cards of the several series, the first card of each series eventually comes into view, ready for a new cycle or period of time, thus making the calendar truly perpetual and without the reversing of any of 105 the parts to start fresh, as for instance at the beginning of a new year.

Having fully described my invention,

what I claim as new, and desire to secure by Letters Patent, is:—

In a device of the class described, a frame including vertical side bars formed, each, of 5 a length of wire bent centrally to form downwardly extended parallel members the lower ends of which are diverged to form feet, spaced horizontal brace bars rigidly se-

cured between the parallel side bar members, and cards suspended from said brace 10 bars.

WILLIAM S. ORTH.
